DATA KEY

Meryl E. Miller, Palos Verdes Peninsula, Calif., assignor
to Datanetics Corporation, Redondo Beach, Calif., a
corporation of California

Filed May 14, 1969, Ser. No. 17,146

Term of patent 14 years

Int. Cl. D14—02

U.S. Cl. D26—5

FIG. 1 is an enlarged perspective view of a data key embodying my new design;

FIG. 2 is a front elevational view of the data key shown in FIG. 1;

FIG. 3 is a top plan view of the data key shown in FIG. 1;

FIG. 4 is a bottom plan view of the data key shown in FIG. 1; and

FIG. 5 is a sectional view, taken along the line 5—5 in FIG. 2 of the data key shown in FIG. 1.

I claim:

The ornamental design for a data key, as shown.
